UNITED STATES PATENT OFFICE.

WILLIAM W. WATSON AND JAMES S. WATSON, OF KANSAS CITY, MISSOURI.

MACHINE FOR MAKING AND LAYING UNDERGROUND TILE.

1,218,727.

Specification of Letters Patent. Patented Mar. 13, 1917.

Application filed May 13, 1916. Serial No. 97,440.

To all whom it may concern:

Be it known that we, WILLIAM W. WATSON and JAMES S. WATSON, citizens of the United States, residing at Kansas City, in the county of Jackson and State of Missouri, have invented certain new and useful Improvements in Machines for Making and Laying Underground Tile, of which the following is a specification.

10 This invention relates to a machine for making and laying underground tile and has for its object to produce a machine of this character which operates efficiently and embodies the desirable features of simplicity, strength, durability and cheapness of construction.

With this object in view the invention consists in certain novel and peculiar features of construction and combinations of parts as hereinafter described and claimed; and in order that the invention may be fully understood reference is to be had to the accompanying drawing, in which—

20 Figure 1, is a central vertical longitudinal section of a machine embodying our invention.

Figure 2 is a top plan view of the same.

Figure 3, is a front view.

30 Figure 4, is an enlarged horizontal section of the cement condensing tube and shows the slot producing knives.

In the said drawings 1 is a suitable frame composed preferably of a pair of parallel bars secured together and adapted to be connected to any suitable tractor or power for operation purposes. Secured rigidly to and depending from said frame is a standard 2, the front edge of which is sharpened as at 3 and said standard is adapted to be partly 40 embedded in the ground and cut its way through the latter as the machine is drawn forward, and secured to the lower end of said standard is a pointed cylinder 4 for producing a cylindrical underground passage, said cylinder having a cross piece 5 at its rear end for a purpose which hereinafter appears.

45 6 is a vertical tube secured to the rear edge of the cutting standard 2, communicating at its lower end with the interior of the pointed cylinder 4 and secured to the rear edge of said tube and to said frame 1 is a feed tube 7, which with tube 6 is of substantially the same width as the standard 2 so that tube 6 and feed tube 7 may offer no material resistance to the travel of the machine.

The upper end of the feed tube communicates with the hopper 8, wherein semi-liquid cement may be deposited or mixed. The lower end of the feed tube communicates 60 with the cylinder 9 of substantially the same diameter as and forming practically a continuation of the pointed cylinder 4, and said cylinder 9 is provided with a longitudinal slit or slot 9^a, and with a pair of central 65 bearings 10 and 11 supported by vertical arms 12 running to the wall of the cylinder. A small guide tube 13 extends through the cross piece 5 of the pointed cylinder 4 and projects beyond the rear end of cylinder 9, 70 and secured on the rear end of said tube is a conical spreader 14, the pointed end of the same extending into the rear end of cylinder 9 and fitting in the bearing 11 so as to be supported in concentric relation to cylinder 9 and to hold the rear end of the tube 75 13 concentrically thereof.

The conical spreader at its point of largest diameter is of substantially the same diameter as the internal diameter of cylinder 9 and is formed with a circumferential recess 15 at its rear end for receiving the front end of a cylindrical cement condensing device 16, the external diameter of said device at its front end being substantially 80 equal to the diameter of the conical spreader at its point of greatest diameter, and at such end is pivoted for vertical movement on a cross piece 17 mounted on the rear end of the guide tube 13. The condensing device or cylinder 16 is of gradually increasing diameter toward its rear end so that as it is drawn through the mass of cement, as hereinafter explained, it will tightly plaster the same against the walls of the passage produced by the pointed cylinder. 95

Pivoted to lugs 18 within the cylinder 16 and at opposite sides of the same is a pair of drain-slot producing knives 19, springs 20 secured to the lugs and bearing against the cylinder 16 and the knives for the purpose of holding the latter projecting outward beyond the rear end of the cylinder as shown in Fig. 4, so that in the travel of the cylinder, said knives shall cut slots in opposite sides of the tile being laid. 100

21 is a cable attached at its rear end to the knives and extending through the guide tube 13 and then around sheave 22 in the lower end of tube 6 up through the latter 110 and over a sheave 23 at the upper end of the same to a lever 24 fulcrumed on lug 25

mounted on the upper end of standard 2, and said lever is provided with a gravity pawl 26 for engaging a stationary toothed sector 27. The arrangement is such that when the lever is drawn back the cable 5 draws the knives inward to inoperative position, the engagement of the pawl with the rear tooth of the sector holding the knives in such position.

10 When it is desired to set the knives in operative position as shown in Fig. 4, the pawl is tripped to permit the springs to throw the knives outward, the pull thereon of the cable swinging the lever to the position shown in Fig. 1. With the parts in this position it will be apparent that should the knives encounter an unyielding obstruction such as the point of a rock they will yield inwardly to avoid injury.

15 Coupled to the rear side of and in line with the tube 7 is a frame 28 within which is journaled a heavy grooved roller 29, this roller being adapted by compression to close the opening produced in the ground by the standard 3 and to pack the loosened ground 25 tightly down upon the cylinder 9, and to coöperate with this roller a heavy drag 30 is coupled to the rear end of the frame 28, this drag extending from the rear end of cylinder 9 to about the rear end of the condensing cylinder 16. The drag 30 offers a 30 resistance to upward movement to the soil under the application of force applied thereto by said slightly tapered cylinder 16.

35 To operate this machine a shallow trench is dug which will about equal the machine in length. The machine is then placed in the trench and if the bottom of the trench is not level the condensing cylinder is free 40 to pivotally assume a position which accommodates the ground level below it, and thus relieve the machine of the necessity of supporting the cylinder 16 in a horizontal position. If the cylinder 16 were rigidly secured 45 in place it is obvious that it would exert considerable injurious leverage at times on the rod 13 to which it is attached.

Assuming that the machine has been set 50 in a trench and the hopper has been charged with cement in semi-fluid condition, it will be seen that as the machine is drawn forward the pointed cylinder will be forced through the soil and produce a cylindrical passage therein. At the same time the cement in and entering the cylinder 9, will 55 seep through the slot of said cylinder and come in contact with the wall of the passage, and the cement being in a semi-fluid condition will flow toward the rear end of the cylinder 9 and out of the same around the 60 cylinder 9 and out of the same around the spreader 14, this discharge of the semi-fluid cement being facilitated by reason of the tendency of the cement seeping through the slot of the cylinder 9 to adhere to the wall 65 of the passage. As the spreader is drawn

through the mass of cement issuing from the rear end of the cylinder 9, it begins the formation of the hollow tile by spreading the cement to approximately the desired wall thickness against the wall of the passage, 70 the cylinder 16 continuing this operation and completing the formation of the tile as at T, and the knives producing drain slots t, in the sides of the tile.

The machine will travel slowly and the 75 cement will be of the quick setting character so that it will set with sufficient hardness to retain its shape after the cylinder 16 has passed by, having acquired sufficient hardness, furthermore, to withstand the cutting 80 operation of the knives without collapsing, it being understood of course that the curved portion of the weighted roller and of the drag tend to compress the overlying soil in the form of an arch so that the soil shall 85 carry its own weight and not impose it directly upon the tile when in its green state.

With a machine of this character the tile can be made and laid underground rapidly and efficiently and we wish it to be understood that while we have illustrated and described the preferred embodiment of the invention we reserve the right to make all changes falling within the spirit and scope 90 of the appended claims. 95

We claim:

1. A machine for making and laying underground tile, comprising a suitable frame, a vertical standard extending downward from the frame and sharpened at its front 100 edge, a cylinder provided with a pointed front end secured horizontally to the lower end of said standard, a hollow cylinder alined with and extending rearwardly from the pointed cylinder and provided with a 105 longitudinal slot in its wall, means to supply semi-fluid cement to the last-named cylinder so that cement may seep through the slot in the wall of the cylinder, and means movable with said cylinders for spreading 110 outwardly the cement which escapes from the rear end of the slotted cylinder when the machine is in motion.

2. A machine for making and laying underground tile, comprising a suitable frame, 115 a vertical standard extending downwardly from the frame and sharpened at its front edge, a cylinder provided with a pointed front end secured horizontally to the lower end of said standard, a cylinder in line with 120 and rearward of the pointed cylinder, means to supply semi-fluid cement to the last-named cylinder, a conical spreader arranged coaxially with said cylinder and adapted to spread outwardly the cement passing rearwardly through the said last-named cylinder, and a condensing cylinder arranged coaxially and extending rearwardly from the 125 conical spreader.

3. A machine for making and laying un- 130

derground tile, comprising a suitable frame, a vertical standard extending downwardly from the frame and sharpened at its front edge, a cylinder provided with a pointed front end secured horizontally to the lower end of said standard, a cylinder in line with and rearward of the pointed cylinder, means to supply semi-fluid cement to the last-named cylinder, a conical spreader arranged coaxially with said cylinder and adapted to spread outwardly the cement passing rearwardly through the said last-named cylinder, a condensing cylinder arranged coaxially of and extending rearwardly from the conical spreader, and one or more knives carried by the condensing cylinder for producing a drain slot or slots in the cement tile.

5 front end secured horizontally to the lower end of said standard, a cylinder in line with and rearward of the pointed cylinder, means to supply semi-fluid cement to the last-named cylinder, a conical spreader arranged coaxially with said cylinder and adapted to spread outwardly the cement 10 passing rearwardly through the said last-named cylinder, a condensing cylinder arranged coaxially and extending rearwardly from the conical spreader, and means for compressing the ground above the said cement receiving and condensing cylinders.

15 6. A machine for making and laying underground tile, comprising a suitable frame, a standard extending downward therefrom, a cylinder secured to the lower end of the 20 standard and adapted for producing a rounded passage underground, a cylinder rearward of the first-named cylinder and provided with a longitudinal slot through which cement may pass, means for supplying semi-liquid cement to said last-named cylinder, a guide tube extending through said last-named cylinder, a vertical guide 25 communicating at its lower end with the guide tube extending through said cylinder, a conical spreader mounted on the rear end of the first named guide tube and projecting part way into the inclosing cylinder, a condensing cylinder pivotally connected to said guide tube rearward of said spreader, 30 a drain-slot producing knives carried by said condensing cylinder, a cable connected to said knives and extending through said guide tubes, and means for operating said cable to withdraw the knives to inoperative 35 position.

35 7. A machine for making and laying underground tile, comprising a suitable frame, a vertical standard extending downwardly from the frame and sharpened at its front edge, a cylinder provided with a pointed 40 end of said standard, a cylinder in line with and rearward of the pointed cylinder, means to supply semi-fluid cement to the last-named cylinder, a conical spreader arranged coaxially with said cylinder and adapted to spread outwardly the cement passing rearwardly through the said last-named cylinder, a condensing cylinder arranged coaxially of and extending rearwardly from the conical spreader, one or more knives carried 45 by the condensing cylinder for producing a drain hole or holes in the cement tile, and means for moving the knives to and securing them in inoperative position.

45 8. A machine for making and laying underground tile, comprising a suitable frame, a vertical standard extending downwardly from the frame and sharpened at its front edge, a cylinder provided with a pointed 50 end of said standard, a cylinder in line with and rearward of the pointed cylinder, means to supply semi-fluid cement to the last-named cylinder, a conical spreader arranged coaxially with said cylinder and adapted to spread outwardly the cement 55 passing rearwardly through the said last-named cylinder, a condensing cylinder arranged coaxially and extending rearwardly from the conical spreader, and means for compressing the ground above the said cement receiving and condensing cylinders.

6. A machine for making and laying underground tile, comprising a suitable frame, a standard extending downward therefrom, a cylinder secured to the lower end of the 60 standard and adapted for producing a rounded passage underground, a cylinder rearward of the first-named cylinder and provided with a longitudinal slot through which cement may pass, means for supplying semi-liquid cement to said last-named cylinder, a guide tube extending through said last-named cylinder, a vertical guide 65 communicating at its lower end with the guide tube extending through said cylinder, a conical spreader mounted on the rear end of the first named guide tube and projecting part way into the inclosing cylinder, a condensing cylinder pivotally connected to said guide tube rearward of said spreader, 70 a drain-slot producing knives carried by said condensing cylinder, a cable connected to said knives and extending through said guide tubes, and means for operating said cable to withdraw the knives to inoperative 75 position.

In testimony whereof, we affix our signatures.
